UNITED STATES PATENT OFFICE.

SOLOMON KARPEN, OF CHICAGO, ILLINOIS, ASSIGNOR TO S. KARPEN & BROS., OF CHICAGO, ILLINOIS, A CORPORATION OF WEST VIRGINIA.

COMBINATION FOLDING BED.

1,115,316.

Specification of Letters Patent.

Patented Oct. 27, 1914.

Application filed January 27, 1914. Serial No. 814,622.

To all whom it may concern:

Be it known that I, SOLOMON KARPEN, a citizen of the United States, residing at Chicago, in the county of Cook and State of Illinois, have invented a new and useful Improvement in Combination Folding Beds, of which the following is a specification.

This invention relates particularly to combination folding beds, such as sofa beds, table beds, etc. In such structures, where three main sections connected by spacing sections are employed, it is desirable to fold the outer main section over the intermediate main section and lock it thereto before performing the next folding operation, which brings the intermediate main section and the outer section into folded relation with respect to the inner main section. Heretofore, difficulty in performing the folding and unfolding operations has frequently been experienced, and the folding structure has been subjected to injurious strains, owing to the fact that the foot-section is frequently improperly locked to the intermediate-section before the second folding operation is performed, thus giving rise to the difficulties of operation and the injurious racking strains upon the bed-structure noted above.

The primary object of the present invention is to insure proper locking of the outer main-section with respect to the intermediate main-section before the folding of the intermediate main-section with respect to the inner or head-section can be completed. The object is preferably accomplished by employing a pair of safety locking levers which, when the bed-structure is in the open condition, lock the intermediate section against folding with relation to the inner section till, in the folding operation, the outer bed-section is, after being folded with relation to the intermediate bed-section, properly locked to the intermediate section, whereupon the safety locking levers are released to permit folding of the intermediate main-section with relation to the rear main-section.

The invention is illustrated in its preferred embodiment in the accompanying drawing, in which—

Figure 1 represents an elevational view of a sofa-bed having one end of the main-frame removed, the bed-structure being shown in a partially folded condition; Fig.

2, a broken elevational view showing the relation of the safety locking levers with respect to the intermediate main-section upon which they are mounted and the adjacent inner spacing section; and Fig. 3, a broken perspective view illustrating the manner in which the locking-arms which serve to secure the outer main bed-section to the intermediate main bed-section in the folded relation serve to release the safety locking-levers from engagement with the inner spacing section to permit the final bed-folding operation to be performed.

In the construction illustrated, A represents the main frame—in this case a sofa frame—which serves as a support for the inner bed-section; B, a seat swingingly connected with said frame; C, a folding bed adapted to be normally housed within the frame and beneath the seat in the folded condition of the structure; and D, a pair of safety-locking-levers mounted on the intermediate main bed section and adapted to prevent the completion of the operation of the folding of the bed until the outer main bed section is properly locked to the intermediate main bed-section in the manner shown in Fig. 1.

The frame A may be of any suitable form. It is illustrated in the form of a sofa-frame, comprising end standards 1 connected together by a box 2 and equipped with a back 3.

The seat B is connected, by links 4, to the front portions of the end-standards 1 of the main frame, and is adapted to swing from the inverted position in front of the frame to an upright position surmounting the box 2.

The folding-bed, in the form shown, comprises a rear main section 5, which usually constitutes a head-section; an intermediate main-section 6; an outer main-section 7, which usually constitutes a foot-section; an inner spacing section 8 linking together the main sections 5 and 6; and an outer spacing section 9 linking together the main sections 6 and 7.

The section 5 is connected, by elbow-links 10, to the box 2; the section 8 is joined by pivots 11 to brackets or hangers 12 connected with the pivotal portion of the seat; the elbow portions of the links 10 are connected by links 13, with the bracket-members 12; and the intermediate main-section 110

6 is connected, by links 14, to the swinging edge-portion of the seat, which, in the sofa-form of the device, constitutes the rear portion of the seat. The seat is shown provided with folding legs 15 operated by levers 16 through the medium of the links 14, as is now understood in the art.

The bars comprising the spacing section 9 are joined by a pivotally-connected truss 17 in a manner well understood in the art. The outer or foot-section 7 of the bed is equipped with legs 18 which are joined, by pivots 19, to the foot-section and actuated by links 20 connected with the outer spacing-section 9. The legs 18 are connected in the usual manner by an arched brace 21. The legs are also equipped with locking-arms 22 provided with notches 23 adapted to engage locking-studs 24 with which the intermediate main-section is equipped. Pivoted locking-pawl 25, which are gravity-operated, may be employed to engage shoulders 26 at the extremities of the arms 22. The auxiliary locking devices 25 come into play when the section 6 is swung to the vertical position in the folding operation, as is known.

The safety locking levers, which are here shown as anti-folding devices, may comprise bars 27 joined by pivots 28 to the bars comprising the intermediate main bed-section 6, the bars 27 having their inner ends equipped with inwardly-turned lateral projections or lugs, 29, and having their outer ends equipped with outwardly-turned lateral projections or lugs, 30. The lugs 29 are adapted to engage shoulders 31 with which the bars comprising the inner spacing-section 8 are provided at their outer ends. Normally, the members 29 rest upon the upper surface of the bars comprising the section 6 and engage the shoulders 31 in the manner shown in Fig. 2.

When the foot-section 7 is folded over the intermediate main-section 6 and the locking-arms 22 are properly brought into locking engagement with the studs 24, the upper walls of the slots 23 engage the cam-lugs 30 of the safety locking-levers 27 and swing the locking-lugs 29 out of engagement with the shoulders 31, thus leaving the structure free to be completely folded in a manner well understood in the art.

From the foregoing description, it will be understood that I preferably employ an anti-folding locking lever which is thrown to the inoperative or released position by the folded-section locking device when the latter is brought into the locking position. Thus, by insuring proper locking of the outer sections in the folded relation, I obviate the great annoyance to the operator and the racking strains upon the structure, which are incidental to an attempt to complete the folding operation and afterward the opening operation, where there occurs a

failure to properly lock the outer sections together in the first instance.

The foregoing detailed description has been given for clearness of understanding only, and no undue limitation should be understood therefrom, but the appended claims should be construed as broadly as permissible in view of the prior art.

What I regard as new, and desire to secure by Letters Patent, is:

1. The combination with a supporting-frame, of a folding-bed adapted to be housed in folded condition in said frame, said bed comprising a plurality of main-sections and a plurality of spacing-sections connecting said main-sections, means for locking the outer main-sections in folded relation, and an anti-folding device adapted to be moved to the inoperative position in the operation of bringing said locking means into locking engagement. 75 80 85

2. In a structure of the character set forth, the combination with supporting means, of a folding-bed comprising an inner main-section, an intermediate main-section, an outer main-section, and spacing sections connecting the intermediate section to the other sections, means for locking the outer main-section in folded relation upon the intermediate main-section, and an anti-folding device adapted to be thrown to the inoperative position in the operation of bringing said locking means into locking position. 90 95

3. In a structure of the character set forth, the combination with supporting means, of a folding-bed structure comprising a plurality of foldably-related bed-sections, locking means for securing one section in folded relation to another section, and an anti-folding device operative to prevent complete folding of the structure and adapted to be thrown to the inoperative position in the operation of bringing said locking means into locking engagement. 100 105 110

4. In a structure of the character set forth, the combination with supporting means, of a folding-bed structure comprising a head-section, an intermediate section, a foot-section, and spacing sections connecting the same, of locking means adapted to secure the foot-section in folded relation on the intermediate section, and an anti-folding device mounted on the intermediate section and serving to prevent premature completion of the folding operation, said anti-folding device adapted to be thrown to the inoperative position in the operation of bringing said locking means into locking engagement. 115 120 125

5. In a structure of the character set forth, the combination with supporting means, of a folding-bed structure comprising a head-section, an intermediate-section, a foot-section, and spacing sections connect- 130

- ing same, of locking means adapted to secure the foot-section in folded relation to the intermediate-section, and an anti-folding lever mounted on the intermediate-section 5 and adapted to prevent premature completion of the folding operation, said lever adapted to be thrown to the inoperative position in the operation of bringing said locking means into locking engagement.
- 10 6. In a structure of the character set forth, the combination of supporting means of a folding-bed structure comprising a head-section, an intermediate-section, a foot-section, and spacing sections connecting 15 same, locking-means serving to secure the foot-section in folded relation to the intermediate-section, and anti-folding levers mounted on the intermediate-section and normally engaging the inner spacing-section 20 in the open condition of the structure, said levers equipped with means adapted to be engaged by said locking means in the operation of bringing the locking means into locking position, thereby throwing the anti- 25 folding levers to the inoperative position.
- 7 In a structure of the character set forth, the combination with supporting means of a plurality of foldably-related bed-sections, locking means for securing two 30 of said sections together in folded relation, and an anti-folding device operative to prevent premature completion of the folding operation and adapted to be released by said locking-means in the operation of bringing 35 the locking means into locking engagement.
8. In a structure of the character set forth, the combination with supporting means, of a plurality of foldably-related bed-sections, locking-means operative to se- 40 cure one section in folded relation to another section, and anti-folding levers mounted on one bed-section and operative to prevent premature completion of the folding operation and adapted to be thrown to the 45 inoperative position in the operation of bringing said locking-means into locking engagement.
9. In a structure of the character set forth, the combination with supporting 50 means, of a folding-bed comprising a head-
- section, an intermediate-section, a foot-section and spacing-sections connecting the same, of locking-arms adapted to secure the foot-section in folded relation to the intermediate-section, and anti-folding levers op- 55 erative to prevent premature completion of the folding operation, said levers mounted on said intermediate-section and adapted to be engaged by said locking-arms and thrown to the inoperative position in the operation of 60 bringing the locking-arms into locking position.
10. In a structure of the character set forth, the combination of a folding-bed comprising a head-section, an intermediate-section, a foot-section, and spacing sections connecting the same, folding-legs connected with the foot-section, locking-arms carried by said legs, locking members carried by said intermediate-section adapted 65 to be engaged by said locking-arms, and an anti-folding lever operative to prevent premature completion of the folding operation, said lever mounted on said intermediate section and adapted to be thrown 70 to the inoperative position by one of said locking-arms in the operation of bringing the same into locking engagement.
11. In a structure of the character set forth, the combination of a frame, and a 80 folding-bed comprising a head-section mov- ably mounted in said frame, a swinging member connected with said frame, an inner spacing-section pivotally mounted on said swinging member, an intermediate 85 main bed-section, a foot-section, an outer spacing-section connecting the foot-section to the intermediate main-section, locking means serving to secure the foot-section in folded relation to the intermediate main- 90 section, and anti-folding levers mounted on the intermediate main-section and adapted to be thrown to the inoperative position by said locking means when said locking means are brought into locking engagement.

SOLOMON KARPEN.
